UNITED STATES PATENT OFFICE.

MARK A. SMITH AND CHARLES F. YAEGER, OF EVANSVILLE, INDIANA;
SAID SMITH ASSIGNOR TO SAID YAEGER.

WIRE-BOUND BROOM.

SPECIFICATION forming part of Letters Patent No. 355,225, dated December 28, 1886.

Application filed January 30, 1886. Serial No. 190,320. (No model.)

To all whom it may concern:

Be it known that we, MARK A. SMITH and CHARLES F. YAEGER, citizens of the United States, residing at Evansville, in the county 5 of Vanderburg and State of Indiana, have invented certain new and useful Improvements in Wire-Bound Brooms; and we do declare, the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of this invention, and is a horizontal section taken across the lower end of the broom-handle. Fig. 2 is a vertical section of a portion of a broom. Figs. 3, 4, and 5 are details.

20 Fig. 6 is a view of a broom complete.

This invention has relation to improvements in brooms; and it consists in the construction, novel arrangement, and adaptation of devices, as hereinafter described, and pointed out in 25 the claim.

The main object of our invention is to provide a firm engagement or connection with the broom-straw and handle at the head of the broom, as well as the neck thereof.

30 In the accompanying drawings, A indicates a broom stick or handle, which may be that of an ordinary broom having its lower end wedge-shape, or beveled and flattened on opposite sides, as indicated at B. This tapering or reduced portion is designed to be let into the 35 head of the broom through the neck thereof, and is provided with one or more transverse perforations, as shown, for the passage of fastening-wires, as will be presently explained.

40 C D indicate the binding or stay wires, which are bent about midway of their length to pass around the opposite edge of the broom-head, and their straight branches overlap each other in a line coincident with the longitudinal center of the head, so as to receive together the 45 loops of the transverse fastening-wires F.

These binding-wires C and D are provided at their opposite or inner ends with short bent arms E, which are designed to be forcibly turned into the straw, and held therein by 50 means of the fastening-wires F. By having these arms E pass on opposite sides of the stick or handle it will be seen that the binding or stay wires will be prevented from drawing out or leaving the head as long as the transverse 55 wires remain in their normal positions. When these binding or stay wires are placed in position upon the broom-head and the branches E forced in position, the wire or wires F are then provided with a loop at one end to receive the overlapped portions of the said binding-wires on one side of the head. The free end of this wire is then passed through the broom and the aperture in the stick or handle, after which it is turned over the wires on the 60 opposite side and into the broom-straw. This transverse fastening is of an approximately S shape, so that the bends at opposite ends 65 will receive the binding-wires on opposite sides of the head.

The neck of the broom-straw may be secured to the stick in the ordinary manner of wiring, and the usual sewing may be applied beneath the fastening at the head.

Having described this invention, what we 75 claim, and desire to secure by Letters Patent, is—

In a broom, the combination, with a stick, of binding-wires passed around the broom-straw and having their ends turned into the 80 straw adjacent to and at opposite sides of the stick, and secured at their overlapping outer portions by the transverse wires, substantially as specified.

In testimony whereof we affix our signatures 85 in presence of two witnesses.

MARK A. SMITH.
CHARLES F. YAEGER.
